UNITED STATES PATENT OFFICE.

LEONARD RODENHAUSEN, OF PHILADELPHIA, PENNSYLVANIA, ASSIGNOR OF ONE-HALF TO FRANK T. KESSLER, OF PHILADELPHIA, PENNSYLVANIA.

TABLE MAT, PAD, &c.

1,123,383.

Specification of Letters Patent.

Patented Jan. 5, 1915.

Application filed February 20, 1914. Serial No. 819,916.

To all whom it may concern:

Be it known that I, LEONARD RODENHAUSEN, a citizen of the United States, residing in the city and county of Philadelphia, State 5 of Pennsylvania, have invented a new and useful Table Mat, Pad, &c., of which the following is a specification.

My invention consists of a table mat, pad or the like, formed of a top member, on 10 which plates, dishes, or other heated objects are adapted to be sustained, and means depending from said member serving to elevate the latter from the table, etc., on which said means are placed, thus preventing the heat of said top member from reaching the top of said table and marring or 15 otherwise injuring the varnish, polish or other finish thereof.

The invention is satisfactorily illustrated 20 in the accompanying drawing, but the important instrumentalities thereof may be varied, and so it is to be understood that the invention is not limited to the specific details shown and described.

25 Figure 1 represents a top plan view, partly broken away, of a table mat, or pad, embodying my invention. Fig. 2 represents a side elevation thereof. Fig. 3 represents an end elevation thereof in folded condition. 30 Fig. 4 represents a section on line *a*—*a* Fig. 1, on an enlarged scale. Fig. 5 represents a section thereof on the line *b*—*b* Fig. 1, on an enlarged scale. Fig. 6 represents a bottom plan view of a section of the mat or pad 35 shown in Fig. 1. Fig. 7 represents an end elevation thereof. Fig. 8 represents a section on line *c*—*c* Fig. 1, on an enlarged scale. Fig. 9 represents a perspective view of a portion of Fig. 8. Figs. 10 and 11 represent 40 longitudinal sections of modifications thereof. Fig. 12 represents a perspective view of another modification thereof. Fig. 13 represents a top plan view of another embodiment of the invention. Fig. 14 represents a 45 diametrical section thereof on line *d*—*d*, Fig. 13.

Similar numerals of reference indicate corresponding parts in the figures.

Referring to the drawings:—1 designates 50 a mat or pad which is composed of the upper member 2, and the depending rim 3, which latter is underneath said member around the periphery thereof and secured

thereto, it being noticed that said rim is adapted to sit on the top of a table, and so 55 elevate said upper member, whereby the latter is removed above the surface of the table top, and so the heat of plates, dishes, or other objects placed on said member as the support thereof will not affect the varnish, 60 polish, or other finish of said table top.

The mat or pad may be formed of sections connected with each other by flexible hinges 4, thus permitting said sections to be folded one on the other, as most plainly 65 shown in Figs. 2 and 3, and the underside of said hinges are covered by the strips 5 which are connected with the frames of the sections, thus concealing said hinges. The sections are also provided with legs 6, which 70 are connected with the undersides of said sections, so as to support the mat or pad intermediate of its borders. The member 2 is also formed with transversely-extending 75 corrugations 7, which serve to strengthen the same, these corrugations when the member is constructed of metal being produced by crimping the same, but the member may be formed of wood, vulcanized fiber, or 80 other material.

The rim 3 may be made of metal or other material bent into the form of a hollow circular body 8, as shown in Figs. 8 and 9, the same being riveted or otherwise secured to said member, as shown in Fig. 8, or it may 85 be made integral therewith, as in Fig. 10. In Fig. 11, I show the rim as formed of circular piece 9 of wood, or other material. In each of the rims of Fig. 8, 9, 10 and 11 are horizontally-extending openings or 90 vents 10 therethrough at intervals to cause the circulation of air through the device, and the discharge of heat from under said member when the latter is occupied by a plate, dish, etc., in heated condition. 95

The sections have coverings 11 of fibrous material such as flannel, felt, etc., the same being secured in the present case to said sections by clips or spurs 12, which are formed with or attached to the inner side 100 of said rim and so concealed leaving the exterior of the covering smooth and unobstructed, and adapted to penetrate the end portions of said covering which are wrapped around said rim and receive said spurs, thus 105 firmly and conveniently attaching the cov-

- ering to the sections. As the coverings pass under the rims, they provide guards for the bottom of the rim preventing abrasion and scratching of the table top. The portion of the coverings 11 around the side of the rim 3 have openings or vents therein, registering with the vents or openings 10 in said rim to permit the escape of heated air through the same.
10. In Fig. 12, the rim 3 is formed of blocks 13 which are connected with the sections and separated at intervals forming the air passages 14 between the same.
15. In Figs. 13 and 14, I show the upper member of a pad or mat of a piece 15 of metal or other material with a rim 16 turned down from the same, the lower end of said rim being seated on a guard 17 of rubber or other soft material, the same preventing abrasion, or scratching of the table top on which the pad or mat is seated. The upper member, Figs. 13 and 14, is formed with corrugations 7 for strengthening purposes, as in the previous instances, it being noticed that in all cases, while the device may be set firmly on a table top, etc., its upper member is adapted to support heated plates, dishes, or other objects in a steady manner, while being elevated and so removed from said top as to prevent the heat from injuriously reaching the latter, while air may pass under said member and through the device and so reduce the temperature to which said member may be subjected by the objects placed thereon. Especially is the table top guarded from the heat of the upper member, since the latter being elevated does not superimpose its weight directly on the table top, nor contact therewith.

Copies of this patent may be obtained for five cents each, by addressing the "Commissioner of Patents, Washington, D. C."

Having thus described my invention what I claim as new and desire to secure by Letters Patent, is:—

1. A table mat composed of a body comprising a top and a side rim, the latter depending from the periphery of said top, a covering of fibrous material extending transversely over said top and having a portion continued downwardly over and around the exterior face of said rim, and means for securing the covering to said rim on the interior thereof.

2. A table mat composed of a body comprising a top and a side rim, the latter depending from the periphery of said top, a covering of fibrous material extending transversely over said top and having a portion continued downwardly over and around the exterior face of said rim, and an additional portion extending inwardly around the bottom edge of said rim enveloping the same, and means for securing the covering to said rim.

3. A table mat composed of a body comprising a top and a side rim, the latter depending from the periphery of said top, a covering of fibrous material extending transversely over said top and having a portion continued downwardly over and around the exterior face of said rim, an additional portion extending inwardly around the bottom edge of said rim enveloping the same and extending upwardly on the interior face thereof, and means for securing said covering in position.

LEONARD RODENHAUSEN.
